[57] CLAIM

The ornamental design for door-mounted mailbox, as shown and described.

DESCRIPTION

FIG. 1 is a front, top and left side perspective view of a door-mounted mailbox showing my new design;

FIG. 2 is a front elevational view;

FIG. 3 is a rear elevational view;

FIG. 4 is a right side elevational view; the opposite side being a mirror image;

FIG. 5 is a bottom plan view;

FIG. 6 is a front top and left side perspective view of a second embodiment of a wall-mounted mailbox showing my new design of FIGS. 1-5 the only difference being is in the curled ends; and

FIG. 7 is a front top and left side perspective view of a third embodiment of a wall-mounted mailbox showing my new design of FIGS. 1-5 the only difference being in the curled end.

The side not shown is the mirror image of the side shown in FIG. 4.

The claimed design for a door-mounted mailbox is positioned with its rear surface against the inside surface of a door and immediately below a mail slot in the door.
